AUTOMATIC VALVE

Theodore A. Cohen, Chicago, Ill., assignor to
 Wheeleco Instruments Co., Chicago, Ill., a corpora-
 tion of Illinois

Application December 31, 1942, Serial No. 470,918

1 Claim. (Cl. 137—139)

1

This invention relates to automatic valves in general and more particularly to such valves as are especially adapted for use where slow opening and instantaneous closing is desired.

In automatic control systems for fuel burners guarded by flame failure safety apparatus, in particular, it is important to have a slow opening fuel valve especially in large fuel feeding mains so as to allow igniting of the burner gradually before the large inrush of fuel is capable of causing an explosion. The closing of the valve, on the other hand, should be instantaneous in event of flame failure at the burner to prevent accumulation of fuel in the combustion chamber which also may cause an explosion.

The primary object of this invention is accordingly to provide such an automatic valve having automatic means for slowly opening the same and for instantaneously closing the valve upon the occurrence of a predetermined contingency such, for example, as flame failure at a burner to which the valve was supplying fuel, or power failure.

Other and further objects of this invention will be more apparent hereinafter as the same becomes better understood from an examination of the specification and claim in conjunction with the accompanying drawing wherein:

Fig. 1 is a vertical sectional view of an automatic valve and automatic operating mechanism therefor embodying this invention;

Fig. 2 is a diagrammatic and schematic view showing the electrical connections of the automatic operating means of the valve.

Referring to the drawing more particularly, reference character 1 designates a valve body cast to provide a flanged inlet 23, a flanged outlet 26 and a partition 2 separating the interior of the body between said openings. The lower part of the body 1, below the partition 2 is cast open and such opening is closed by a plate 1a bolted to a flange on said body. The upper part of the body 1, above the partition 2, is cast open and provided with a flange around the opening to which is bolted a casting 2a which acts to close said opening.

The partition 2 is apertured to provide a valve opening and seat adapted to receive a valve disk 3. The disk 3 is mounted on the lower end of a plunger 5 and is normally held in closed position by a spring 4. The plunger 5 extends upwardly through a bearing 6 in the bottom of casting 2a and is provided, on its upper end, with a circular armature 8. A bellows 7 surrounds the plunger 5, above the bearing 6 in the casting 2a

and below said armature 8 and is sealed to said casting and armature to prevent the escape of fuel gases, from the body, through the bearing 6, to the surrounding atmosphere.

The upper part of the casting 2a acts to support an operating electro-magnet 11 having a winding 12 and an operating stem 13. The stem 13 extends upwardly through a bearing 13a in the casting 2a aligned above the bearing 6 and said stem 13 is operated by mechanism as follows:

An electric motor 16 is mounted on the casting 2a and is provided with a gear drive 17 which operates a drive shaft 18 having a cam 19. A cam follower 20 is mounted upon a laterally extending shaft 21 attached to the upper end of stem 13.

A limit switch 9 is mounted on the base of casting 2a and cooperates with an operating stud 10 on the armature 8 so that when the valve is closed said switch will close and when said valve opens as hereinafter described contact 9a of said switch will be opened.

A second limit switch 14 is mounted at the top of casting 2a and cooperates with an operating stud 15 on the stem 13 of the operating magnet so that when said magnet reaches its extreme upward movement said switch will be opened by opening contact 14a and as long as said magnet is below its extreme upward position said switch will remain closed energizing motor 16.

The electrical connections are as shown in Fig. 2 wherein line supply 25 is connected to magnet winding 12 through flexible leads 12a. The motor 16 is also connected across the line 25 in such manner as to be energized if either limit switch 9 or 14 is closed.

Operation

49 The valve 3 is normally closed under the action of spring 4 as shown in Fig. 2. Upon power being supplied from line 25, winding 12 of electro-magnet 11 is energized but magnet 11 being a tractive electro-magnet it does not lift armature 8. Motor 16 is energized through limit switch contact 9a. Motor 16 revolves cam 19 whereupon shaft 18 moves downward until magnet 11 is in contact with armature 8 at the lowest dwell of cam 19. The motor 16 continues to revolve cam 19 whereupon shaft 18 rises moving magnet 11 upward taking armature 8 therewith. Armature 8, through shaft 5, lifts valve disk 3 against spring 4. When shaft 18 is at maximum rise of cam 19, limit stud 15 opens contacts 14a of limit switch 14 thereby deenergizing motor 16 leaving

valve disk 3 in raised position against compression of spring 4. Valve 3 is then held open. If a power failure occurs in the supply to the valve unit at 25 as in the case of flame failure where a burner control apparatus is used such as shown and described in connection with my co-pending application Ser. No. 57,321, filed January 2, 1936, for Control apparatus, now Patent Number 2,343,-001, granted February 29, 1944, magnet winding 12 is deenergized whereupon armature 8 is released and spring 4 snaps down valve disk 3 to close valve and shuts off fuel supply. When armature 8 reaches position shown in Fig. 2 with valve closed, limit stud 10 strikes limit switch 9, closing contact 9a which again completes the circuit to motor 16 so that upon the resumption of power supply at 25 the opening cycle will be repeated. Thus a valve action is secured which is slow opening and snap closing.

I am aware that many changes may be made and details varied without departing from the principles of my invention and I therefore do not wish to be limited to the details shown and described.

I claim:

The combination of an automatic valve comprising a valve body, a valve closure therein, spring means normally acting to close same, an armature connected to said closure, an electric

motor, a reciprocable electro-magnet adapted to adhere to said armature, when energized and adjacent thereto, driving means for reciprocably moving said electro-magnet in a straight line, connecting said motor and electro-magnet, to retract the same, together with said closure, against the action of said spring to open the valve, switch means adapted to open a circuit to said motor when said electro-magnet has been moved to its extreme retracted position, electrical connections for said motor and electro-magnet to a source of power whereby failure of said source will deenergize the electro-magnet to permit said spring to close said valve and so connected to said switch means as to permit the motor to be stopped as aforesaid without deenergizing said electro-magnet when said source is present and a second switch means so connected to said source and the first switch means as to energize said motor when said source is again turned on and the valve is closed even when the electro-magnet is in extreme retracted position and the first switch means is open to permit said electro-magnet to move back to said armature to reengage the same and again open said valve upon the retractive movement of the electro-magnet, said electro-magnet and armature forming an electro-magnetic detent or the like.

THEODORE A. COHEN.
